United States Patent Office

Des. 184,885
Patented Apr. 14, 1959

184,885

HOLSTER FOR FIREARMS OR THE LIKE

Melvin G. Miller, Houston, Tex.

Application March 12, 1958, Serial No. 49,996

Term of patent 14 years

(Cl. D30—1)

I claim:

The ornamental design for a holster for firearms, or the like, as shown.
